Frank Dutcher,
By O.S. Battison Son

Inventor

Attorney

UNITED STATES PATENT OFFICE.

FRANK DUTCHER, OF MCKEESPORT, PENNSYLVANIA.

RAILWAY SIGNAL TORPEDO.

Application filed April 14, 1924. Serial No. 706,360.

To all whom it may concern:

Be it known that I, FRANK DUTCHER, a citizen of the United States, residing at Versailles Boro., McKeesport, in the county 5 of Allegheny and State of Pennsylvania, have invented certain new and useful Improvements in Railway Signal Torpedoes, of which the following is a specification, reference being had therein to the accompanying 10 drawing.

This invention relates to improvements in railway signal torpedoes, and it particularly pertains to the construction of a rail engaging strap and its clip.

15 The primary object of the present invention is the construction of a two-part spring rail engaging strap, so that when it is slipped in the clip it is automatically locked therein.

20 The improvement more specifically relates to a clip having openings, and a two-part spring strap, each part provided with a projecting member adapted to interlock with the said clip.

25 Specifically the improvement consists of a clip having strap openings and a two-part strap, each part having its end doubled, and a spring struck up from the strap, whereby when the doubled portion is pushed through 30 the openings in operative position the said spring will engage a part of the clip and hold it in its position.

In the accompanying drawing:

Figure 1 is an enlarged cross sectional 35 view of a torpedo which shows my improvement attached thereto.

Figure 2 is a plan view of Figure 1.

Figure 3 shows another form of clip constructed to receive the improved strap.

40 Figure 4 is a plan view of another form of clip showing my improved two-part strap applied to it.

Many improvements have heretofore been made to facilitate the attachment of a strap 45 to a torpedo clip, for the purpose of holding it in operative position. The present improvement is very effective in operation, cheaply constructed and quickly applied.

The improvement has been shown particularly with a circular torpedo, but I desire it understood that the said improvement may be applied to any type of torpedo 50 and to any type of clip without changing the invention.

55 In the drawings; 1 indicates a case circular in form, and in this form of case is

shown a surrounding strengthening ring 2.

As shown in Figures 1 and 2 the clip 3 is united to the case by having the ring 2 extending below the case as shown at 4, 60 the extending part of the ring holding the clip in position. This feature of the invention is the subject matter of a co-pending application bearing Serial Number 706,358 filed April 14th, 1924 in which it is claimed, 65 and therefore no claim is made for it in this application.

In the form of clip shown it is provided with a central opening 5 and two oppositely disposed openings 6, through which openings the upper ends of a two-part strap 7 passes.

The upper ends of the two parts of the strap are doubled as shown at 8 making a somewhat U-shape, the doubled part 75 bracing the part 9 of the clip.

The upper end of each part of the strap has struck outward from it the two lips or projections 10, which lips or projections engage the parts 9 of the clip and hold it 80 from inward movement, whereas the doubled parts of the clips hold them against outward movement.

The form of clip here shown has its center bulged outward forming a flat surrounding 85 part 11 that is in engagement with the extended part 4 of the ring 2. This construction is not at all necessary or essential to the operation of my present improvement.

I desire it understood that modifications 90 of the present improvement may be made so long as they are within the scope of the appended claims.

In Figure 3 another form of clip is shown in which its edges 12 are turned around the 95 edge of the case 1' and thereby holding it in position thereon.

In Figure 4 another form of clip is shown elongated in shape, and attached in any manner to the case (not shown).

The two parts 7 of the strap are applied transverse the clip 3'.

In each form of clip there is a central opening 5 and oppositely disposed openings 6, which are given the same designating 100 numbers in all the figures of the drawings.

Having thus described my invention what I desire to secure and claim by Letters Patent is:

1. A railway signal torpedo, comprising 110 a case, a clip applied thereto and having a strap opening, and a two-part strap applied

through the said opening, one of the members having spring interlocking parts for holding the said straps in position on the clip.

5. 2. A railway signal torpedo comprising a case, a clip connected to the case having strap openings, a two-part strap passing through said openings, each part of the strap having projecting spring members interlocking with the clip for holding it in position thereon.

10. 3. A railway signal torpedo comprising a case, a clip attached to the case, the clip having two sets of openings, a two-part strap, each end of the strap constructed to interlock with that part of the clip locked between the said openings.

15. 4. A railway signal torpedo comprising a case, a clip attached to the case said clip having three openings, a two-part strap passing through the said openings, each end of the strap constructed to interlock with the clip between the said openings.

20. 5. A railway signal torpedo comprising a case, a clip attached to the case, a clip having a central and two side openings, a two-part strap having its upper extremities

doubled around the clip between the said openings, each part of the strap having a projection engaging the outer side of the 30 clip between the said openings.

25. 6. A railway signal torpedo comprising a case, a clip attached to the case, the clip having a central and two side openings forming a transverse bar, a two-part strap, the upper end of each part of the strap doubled around the said transverse extending portion of the clip, each end of the strap having struck from it an outwardly extending projection engaging the outer sides of 35 40 the transverse part of the clip.

15. 7. A railway signal torpedo comprising a case, a clip attached to the case, the clip having a central and two side openings forming a transverse bar, the upper end of 45 each part of the strap doubled around the transverse bar, and each bar of the strap having an inwardly extending struck up part in engagement with the said transverse bar.

In testimony whereof I hereunto affix my signature.

FRANK DUTCHER.
